UNITED STATES PATENT OFFICE.

WILLOUGHBY W. PHILLIPS, OF SHONGO, NEW YORK.

GATE.

SPECIFICATION forming part of Letters Patent No. 242,149, dated May 31, 1881.

Application filed March 23, 1881. (Model.)

To all whom it may concern:

Be it known that I, WILLOUGHBY W. PHILLIPS, a citizen of the United States, residing at Shongo, in the county of Allegany and State 5 of New York, have invented certain new and useful Improvements in Gates; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification, and in which—

15 Figure 1 is a side elevation of my improved gate, and Figs. 2, 3, and 4 are detail views of the same.

This invention has relation to that class of gates which may be termed "crane-gates," 20 having for its object, among other things, to support and permit of the sliding of the gate independently of but upon the crane, and to enable the gate-adjusting mechanism to act automatically as the gate is elevated or placed 25 at the desired height to swing clear of snow or other obstruction in the way of the opening of the gate; and it consists of the detailed construction and combination of parts, substantially as hereinafter more fully set forth and 30 claimed.

Referring to the accompanying drawings, A indicates the gate, in the main of the usual 35 construction of this class of gates, and having affixed upon its top edge a horizontal board, a, with its sides projecting beyond the gate and forming flanges.

To the gate is provided a latch, B, in the form 40 of a lever, with the preponderance of weight on the forward arm of the lever, to cause the automatic descent of that end of the lever when the hand is removed from its knob b. It is pivoted at or near its middle to a suitable lug fixed on the horizontal bar a', next to the top bar, a², of the gate, and is so constructed 45 that it is carried back under the upper bar of the crane when the gate is slid back in the act of opening. At the rear end of the lever B is a cut-away portion to form a shoulder, b', which, when the forward end of the lever is let fall, 50 passes up in front of a cross-bar of the crane to prevent endwise movement of the gate when

the gate is closed, and thus prevent the disengagement of its catch or tongue c from the mortised gate-post C.

It is obvious that by lifting the forward or 55 knob end of the lever or latch B its rear or shouldered end will be freed from the crane, by which the gate is connected to the hinge-post, and the gate can then be slid back sufficiently to disengage its catch or tongue from 60 the post C and permit of the opening of the gate.

D is the crane, which consists of upright end bars, d d', each duplicated, as seen in Figs. 2 and 3, connected together by diagonal parallel 65 bars d², and a horizontal bar, d³; secured between the upright parallel bars d d' a short distance below their upper ends. Within the parallel bars d d' are hung frictional rolls d⁴ d⁴, arranged in the same horizontal plane, and 70 upon which the gate is supported and adapted to have endwise movement. Cleats arranged one between the oblique bars d² at d⁴, and the others, d⁶ d⁷, arranged respectively between the lower ends of the uprights d, and near 75 the lower ends of the uprights d', serve to hold the gate in position upon its rolls in the crane. Eyes or staples e e are fastened to one side of the rear end of the crane D, to enable the hanging of the latter upon a staple-shaped rod, f, 80 with its bent ends secured in the post E, and thus allow the gate to be slid past the post.

Upon the inside of the hinge-post E is the gate-adjusting device, which consists of parallel notched or toothed plates F fastened to the 85 sides of a correspondingly-notched bar, F', with intermediate recesses g between the teeth of the parallel plates F, as clearly seen in Fig. 3, to receive the rod f, as shown in the same figure, when supporting the gate-crane upon 90 plates F. The device F F' is linked to the outstanding projection or piece F² on the post E by pivoted links F³, to enable the device F F' to move toward and away from and embrace the rod f upon which the crane is hung. The 95 device F F' is so connected to the offset on the post as to permit its links F³ to occupy an upwardly-inclined position, by which it will be noticed that as the gate is lifted the said device will readily move inwardly and upwardly 100 and permit the upper eye of the crane to pass the coincident tooth of the said device, when

the latter will automatically return to its former position and catch and support the crane-eye upon the top of the said tooth, upon which it may be supported upon releasing the gate. In like manner the gate may be adjusted to any tooth above, and thus permit of holding it at any desired height necessary to enable it to swing clear of snow or other obstruction in the way of opening it. The parallel projecting teeth of the automatic ratchet drop on opposite sides of and embrace the rod *f*. In this position the eye of the gate-hinge rests and turns directly on the teeth. The gate is thus brought close to the gate-post, and there is no liability to get broken or knocked out of position.

It will be further noticed that the gate is supported upon and moves independently of the crane by which it is connected to the hinge-post. The gate *a* has its upper bar, *a*², placed between the upper ends of the pairs of vertical side bars, *d d'*, and the upper ends of said vertical bars abut against the projecting edges of the horizontal cap *a*. Between and near the lower ends of the vertical bars *d* the cleat or supporting-block *d'* is fixed, so that the lower edge of the gate-board *a*³ next the bottom board rests on it, while the extreme ends of said vertical bars are carried below the block *d'* and embraces the bottom board between them. The gate is thus supported so that it is prevented from sagging or in anywise getting out of order, so that it would be hindered or obstructed when slid back through the crane. The several supports and bearings arranged in the crane are arranged as counter-supports, which give stability and permanency to the construction of the crane, so that the latter will not

easily get out of order. Being thus staunchly made, and all the parts well supported, I am enabled to fix the hinge-eyes on the side of the crane and hinge the gate to the side of the post, so that the said gate may be slid back past the side of the post, and thus obviate the necessity for a double post, as is required in sliding gates of ordinary construction.

Having thus fully described my invention, I claim and desire to secure by Letters Patent—

1. The combination, with a sliding gate and its supporting-crane, of a latch, *B*, constructed with one of its ends heavier than the other, and pivoted at or near its middle to one of the horizontal bars of the gate, and sliding back into the crane with the gate when the latter is opened and when the gate is closed, and, dropping automatically, bringing its inner end to abut against the outer end of the horizontal bar of the crane, and thus locking the gate, substantially as set forth.

2. The combination, with the gate provided with hinge-eyes, and the rod or extended pintle *f*, fixed on the post *E*, of the automatic ratchet or pawl *F*, pivoted to the post, and constructed with parallel teeth, which drop on opposite sides of and embrace the rod or pintle *f* and support the hinge-eye of the gate, as set forth.

In testimony whereof I affix my signature in presence of two witnesses on this 14th day of March, 1881.

WILLOUGHBY W. PHILLIPS.
